UNITED STATES PATENT OFFICE.

CHARLES L. DREHER, OF SOUTH NORWALK, CONNECTICUT.

SANITARY SEAT-COVER FOR RAILWAY-COACHES.

1,051,566.

Specification of Letters Patent.

Patented Jan. 28, 1913.

Application filed June 10, 1912. Serial No. 702,868.

To all whom it may concern:

Be it known that I, CHARLES L. DREHER, a citizen of the United States, residing at South Norwalk, in the county of Fairfield and State of Connecticut, have invented a new and useful Improvement in Sanitary Seat-Covers for Railway-Coaches; and I do hereby declare the following, when taken in connection with the accompanying drawings and the characters of reference marked thereon, to be a full, clear, and exact description of the same, and which said drawings constitute part of this application, and represent, in—

15 Figure 1 a perspective view of a car-seat provided with a sanitary seat-cover constructed in accordance with my invention. Fig. 2 a view in broken vertical section showing the mode of attaching the upper 20 end of the flexible cover to a seat. Fig. 3 a plan view of my improved cover in the form in which it is offered for sale, its central portion being broken away. Fig. 4 a view of the cover in transverse section on 25 the line *a—b* of Fig. 3. Fig. 5 a detached plan view of the retaining-rod with its central portion broken away. Fig. 6 a broken view in elevation of the upper portion of the paper cover-strip, showing it 30 as provided with flaps which are represented in their folded positions by full lines, and in their open positions in broken lines.

My invention relates to an improvement 35 in temporary sanitary covers designed primarily to be used in covering the seats of railway coaches, the object being to provide a simple, convenient and effective cover constructed with particular reference to being supplied to the trade at a trifling cost, 40 and to being rolled into compact form in which it may be sold in an automatic vending machine, if desired, and in which it may be readily carried by a traveler in his hand or grip.

45 With these ends in view my invention consists in a sanitary seat-cover having certain details of construction and combinations of parts as will be hereinafter described and pointed out in the claims.

50 In carrying out my invention as herein shown, I employ a cover retaining-rod 2 made of heavy wire, having a straight central or body-portion and formed at its ends with tapering retaining-fingers 3 corresponding to each other in length and by 55 preference tapered by flattening them in

the same plane as shown in Fig. 5. The rod 2 may be varied in length as desired, but ordinarily it will substantially correspond to the width of half the back 4 of an ordinary car-seat 5. The upper end of a long sheet of tough paper 6 forming the temporary seat-cover is folded over the rod 2 and secured thereto by clips 7 or in any other convenient and effective manner. If desired, a thin, light, cheap, woven fabric might be used in place of paper for the temporary seat-cover 6. The cover 6 is made long enough to entirely cover half of the width of the back 4 and seat-cushion 70 8 of an ordinary car-seat, and to provide for tucking a portion of the sheet between the lower edge of the back 4 and the rear edge of the seat-cushion 8. The opposite edges of the upper end of the cover strip 6 are correspondingly cut away to form large clearance-notches 9, whereby the upper end of the strip is reduced in width to permit the employment of a retaining-rod 2 of less length than the full width of the strip which permits two seat-covers to be employed at the same time upon the same car-seat without any interference of their upper ends with each other, and also permits their adjacent inner edges to be overlapped if desired. 80 The narrowing of the upper end of the strip 6 also permits the tapering fingers 3 of the rod 2 to be entered into the outer coils of the strip 6 when the same is rolled up as shown in Fig. 4 so as to avoid the necessity of using any other means than the said fingers for maintaining the strip in the form of a roll in which it may be conveniently vended and carried. As shown 85 in Fig. 6, the edges of the strip are folded 90 inward throughout its length to form flaps 10 which increase the available width of the strip when in use, but permit the length of the roll when the device is not in use, to be kept within convenient limits. 95

100 My improved sanitary-seat cover is supplied to the trade in the form of a roll as shown in Fig. 3. In using it, it is unrolled and the tapering fingers 3 of its rod 2 are thrust from rear to front under the cleat 105 11 extending along the upper edge of the car-seat 4, ordinary car-seats being provided with such cleats not only as a matter of finish for the seats, but also for convenience in holding the tickets of passengers. 110 The strip 6 is then unrolled and carried down over the front of the back 4 and tucked

from front to rear between the lower end of the back 4 and the rear edge of the seat-cushion 8. The strip is then carried forward over the seat-cushion 8 and allowed to 5 hang down in front of the same.

As the paper employed will be tough in its character, my improved seat-cover may be used again and again, if desired, but it is intended to supply it at such a low cost 10 to the traveler that he will leave it on the seat on leaving the car, after it has served to protect his garments from the dirt and dust which are apt to cover the plush of car-seats. My improved sanitary seat-cover 15 will also effectively protect the traveler against possible infection from germs lodged in the heavy plush coverings of car-seats.

I claim:—

1. As a new article of manufacture, a 20 sanitary seat-cover consisting of a strip of flexible material adapted to be formed into a roll when not in use and provided at the respective corners of its upper or outer end with wedge-like retaining-fingers adapted 25 in thickness to be inserted between the upper edge of the back of a car-seat, and a cleat applied thereto, whereby the said retaining-fingers may be thrust under the cleat of a car-seat for securing a sanitary 30 seat-cover thereon.
2. As a new article of manufacture, a sanitary seat-cover consisting of a strip of flexible material adapted to be formed into a roll when not in use and provided at its 35 upper end with a retaining-rod made of

wire and consisting of a straight central-portion substantially corresponding in length to the width of the upper end of the said strip which is attached to it and formed at its ends with tapering fingers adapted to 40 be inserted into the upper edge of the back of a car-seat, the upper end of the strip being cut away at its opposite edges to form clearance-notches to permit the insertion of the ends of the said fingers into the outer 45 coils of the strip to retain the same in the form of a roll.

3. As a new article of manufacture, a sanitary seat cover consisting of a strip of flexible material adapted to be formed into 50 a roll when not in use, and provided at its upper end with a retaining-rod made of wire and consisting of a straight central-portion conforming in length to the width of the upper end of the strip which is attached to it and formed at its ends with 55 tapering fingers adapted to be inserted into the upper edge of the back of a car-seat, the opposite edges of the upper end of the said strip being cut away to form clearance-notches, and the opposite edges of the strip formed with flaps folded inward when the strip is rolled.

In testimony whereof, I have signed this specification in the presence of two subscribing witnesses.

CHARLES L. DREHER.
